UNITED STATES PATENT OFFICE.

WILLIAM D. KYLE AND LEM E. HENDEE, OF MILWAUKEE, WISCONSIN, ASSIGNORS TO LINE MATERIAL COMPANY, OF SOUTH MILWAUKEE, WISCONSIN, A CORPORATION OF WISCONSIN.

INSULATOR.

Application filed June 24, 1922. Serial No. 570,736.

This invention relates to insulators particularly adapted for attaching wires to buildings or other supports, and has for its object to provide an inexpensive device having the requisite strength and insulating properties and being easily attached to the support and the wires without material injury thereto.

The invention further consists in the several features hereinafter set forth and more particularly defined by claims at the conclusion hereof.

In the accompanying drawings, Fig. 1 is a side elevation of an insulator embodying the invention;

Fig. 2 is a transverse sectional view of the insulator taken on the line 2—2 of Fig. 1; and

Fig. 3 is a longitudinal sectional view of a modified form of insulator.

In these drawings 10 indicates the body of the insulator here shown in the form of a ring spreading out to form a broad flat base 11 to have a bearing against the wall or part 25 to which the insulator is secured.

A metal attaching member 12 has its end 13 threaded to form a wood screw and is secured in the body of the insulator. As shown, the member 12 has a looped portion 30 14 which is permanently secured in the body and forms a metal core for the insulator body. The insulator body may be formed of any suitable insulating material, such as porcelain or a hardened plastic. The opening 15 formed in the body permits the wire being passed through the insulator at different angles of approach without requiring a sharp bend in the wire with a consequent weakening thereof.

Where the body 10 of the insulator is formed of porcelain or other similar material, then the threaded attaching member may be inserted in the hard body, as shown in Figs. 1 and 2, by providing an annular slot 16 and a transverse slot 17, or as shown in Fig. 3, where the attaching member does not extend far enough to form an eye, a slot 19 communicating with a bore 18 may be provided. In either of these cases the slots 50 may be filled with suitable cement 20 after the loop ended attaching member has been put in place.

The insulator body may also have a notch 22 therein, preferably at its outer end, for assisting in holding or tying the line wire. 55

With a broad flat base, this insulator, in either of the forms shown, may be screwed up against the side of a building by starting the screw and then inserting a rod, a screwdriver or other suitable implement in the opening and turning this implement. The broad flat base gives rigidity to the device and avoids bending of the screw shank.

The invention provides an inexpensive insulator well adapted for the purpose intended 65 and not liable to injury.

What we claim as our invention is:

1. An insulator, comprising a body of insulating material having a transverse wire-receiving aperture and a support-engaging base, there being a slot in said insulator body including a curved portion about said aperture adjacent the outer end of said insulator body, and an attaching member including a single threaded wood screw shank projecting 75 from the base of said insulator body and having a hooked end disposed and permanently secured within the curved portion of said slot to reinforce said aperture and to retain said attaching member in said insulator body against relative rotation for turning the threaded shank of said attaching member into a support by the rotation of said insulator body.

2. An insulator, comprising an insulator 85 body having a transverse wire-receiving aperture and a support-engaging base, there being a slot in said insulator body including a curved portion about said aperture, and an attaching member having a single threaded screw shank projecting from the base of said insulator body and having a looped end portion disposed and permanently secured within the curved portion of said slot to reinforce said aperture and to retain said attaching member in said insulator body against relative rotation for turning the threaded shank of said attaching member into a support by the rotation of said insulator body. 95

In testimony whereof, we affix our signatures.

WILLIAM D. KYLE.
LEM E. HENDEE.
